US0D1083987S

(12) **United States Design Patent** (10) Patent No.: **US D1,083,987 S**
 Donini et al. (45) Date of Patent: ** *Jul. 15, 2025

(54) **DISPLAY SCREEN OR PORTION THEREOF WITH GRAPHICAL USER INTERFACE**(71) Applicant: **Deere & Company**, Moline, IL (US)(72) Inventors: **Mario L. Donini**, Bettendorf, IA (US); **Matthew T. Wold**, Coal Valley, IL (US); **Kent S. Brown**, Sherrard, IL (US); **Victoria M. Householder**, Milan, IL (US)(73) Assignee: **DEERE & COMPANY**, Moline, IL (US)

(*) Notice: This patent is subject to a terminal disclaimer.

(**) Term: **15 Years**(21) Appl. No.: **29/912,529**(22) Filed: **Sep. 20, 2023**(51) LOC (15) Cl. **14-04**

(52) U.S. Cl.

USPC **D14/485**

(58) Field of Classification Search

USPC **D14/485-495**

Primary Examiner — Rachel A. Voorhies*Assistant Examiner* — Gary N Chamberlin(74) *Attorney, Agent, or Firm* — KLINTWORTH & ROZENBLAT LLP(57) **CLAIM**

The ornamental design for a display screen or portion thereof with graphical user interface, as shown and described.

DESCRIPTION

The sole FIGURE is a front view of a display screen or portion thereof with graphical user interface according to our claimed design.

The evenly dashed lines, which depict portions of the graphical interface, and the unevenly dashed lines, which depict the display screen, form no part of the claimed design.
